UNITED STATES PATENT OFFICE.

ELIA B. IGNATIUS, OF PITTSBURGH, PENNSYLVANIA.

CORSET-COVER.

1,208,787.

Specification of Letters Patent. Patented Dec. 19, 1916.

Application filed October 8, 1915. Serial No. 54,819.

To all whom it may concern:

Be it known that I, ELIA B. IGNATIUS, a citizen of the United States, residing at Pittsburgh, in the county of Allegheny and State of Pennsylvania, have invented certain new and useful Improvements in Corset-Covers, of which the following is a specification.

This invention relates to corset covers, or brassières, and has for its object to provide a garment of such type, in a manner as hereinafter set forth, having means whereby the same can be secured in position without the employment of hooks and eyes, and further having elastic elements to arrest the projecting of the flesh of the back over the top of a corset under such conditions overcoming the bulging of the back of a waist when fitted upon a person.

Further objects of the invention are to provide a corset cover which is simple in its construction and arrangement, close fitting, efficient and convenient in its use, and inexpensive to manufacture.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—Figure 1 is a front elevation of a corset cover, in accordance with this invention, illustrating the same fitted. Fig. 2 is a rear elevation of a corset cover, in accordance with this invention, illustrating the same fitted. Fig. 3 is a side elevation of a corset cover, in accordance with this invention.

Referring to the drawings in detail the corset cover comprises a front 1, which is of a permanent contour to conform to the bust of a person and has a V-shaped neck opening 2. The front 1 is extended as at 3, 4, to provide a pair of shoulder straps, and the rear ends of said straps are connected together at 5 whereby when the cover is fitted the connected portions 5 will be positioned at the small of the back.

Connected to the rear ends of the shoulder straps 3, 4, are a pair of elastic retaining

members 6, 7, having transverse stays 8. The elastic retaining members 6, 7, are of a length, when the corset cover is fitted, to extend upon the front 1, as at 9. The free end 60 of each of the retaining members 6, 7, has connected thereto a flexible strap 10 and when the members 6, 7, are in position the strap 10 of one member overlaps the strap 10 of the other member, as illustrated at 11, 65 Fig. 1.

Each lower corner of the front 1 has secured thereto, as at 12, a band 13, and when the corset cover is fitted, each band extends around the waist of a person and the free 70 ends of the bands are brought to the front of the waists and secured together or to the corset in any suitable manner, under such conditions retaining the lower portion of the cover fitted.

The front 1 has a flexible tab 14, which may be secured by any suitable means to the corset whereby the front is held down and instead of securing the ends of the band 13 together, the said ends 13 can be 80 secured to the tab 14 if desired.

The retaining members 6, 7, are employed to confine any flesh of the back which may project over the top edge of the corset and thereby over-coming any bulging of a waist 85 when the latter is worn.

Owing to the permanent contour of the front, that is to say, providing the front of a shape corresponding to the bust, the front will snugly fit when the cover is worn 90 and overcome an unsightly appearance when wearing a tight fitting waist.

As the corset cover is secured in position at the front of a person it is obvious that it can be conveniently fitted when desired. 95

What I claim is:—

1. A corset cover comprising a front of a permanent contour corresponding to the contour of the bust, a pair of shoulder straps having their front ends secured to 100 the top of the front and secured together at their rear ends, a pair of oppositely extending inclined elastic retaining members connected at their upper ends to the rear ends of the shoulder straps and of a length 105 to extend from the back of a person to overlap the said front, overlapping straps projecting from said retaining members and adapted to be secured together for the purpose of maintaining the retaining members 110 in position, and bands connected to said front and adapted to encircle the waist of

a person and be secured together to maintain the lower portion of the front in position.

2. A corset cover comprising a front of a permanent contour corresponding to the contour of the bust, a pair of shoulder straps having their front ends secured to the top of the front and secured together at their rear ends, a pair of oppositely extending inclined elastic retaining members connected at their upper ends to the rear ends of the shoulder straps and of a length to extend from the back of a person to overlap the said front, overlapping straps projecting from said retaining members and

adapted to be secured together for the purpose of maintaining the retaining members in position, bands connected to said front and adapted to encircle the waist of a person and be secured together to maintain the lower portion of the front in position, and a tape depending from the bottom of the front and adapted to be secured to a corset to arrest upward movement of the front.

In testimony whereof I affix my signature in the presence of two witnesses.

ELIA B. IGNATIUS.
